Primary Examiner — John Windmuller(74) *Attorney, Agent, or Firm* — Patton Boggs LLP; Carl A. Forest; Robert P. Ziemian(57) **CLAIM**

The ornamental design for a tie wrap for bundling objects, as shown and described.

DESCRIPTION

FIG. 1 is a front perspective view of a tie wrap for bundling objects showing my new design, which is symmetrical with a rear perspective view;

FIG. 2 is a side view thereof, which is symmetrical with an opposite side view;

FIG. 3 is an end view thereof, which is symmetrical with an opposite end view; and,

FIG. 4 is an enlarged partial front perspective view thereof.
